UNITED STATES PATENT OFFICE.

JOHN E. MITCHELL, OF PULASKI, VIRGINIA.

CONCRETE GRAVE-VAULT.

1,371,323.

Specification of Letters Patent.

Patented Mar. 15, 1921.

Application filed October 14, 1919. Serial No. 330,546.

To all whom it may concern:

Be it known that I, JOHN E. MITCHELL, a citizen of the United States, residing at Pulaski, in the county of Pulaski and State 5 of Virginia, have invented certain new and useful Improvements in Concrete Grave-Vaults; and I do hereby declare the following to be a full, clear, and exact description of the invention, such as will enable others 10 skilled in the art to which it appertains to make and use the same.

This invention relates to grave or burial vaults and the primary object of the invention is to provide an improved concrete 15 grave or burial vault formed of a plurality of sections which can be readily assembled.

Another object of the invention is to provide an improved concrete burial vault formed from a plurality of interfitting sections which are so formed that when the 20 same are placed in operative position, displacement thereof is absolutely prevented.

A further object of the invention is to provide an improved sectional concrete burial 25 vault of the above character, which is durable and efficient in use, one that is simple and easy to manufacture, and one that can be placed upon the market at a reasonable cost.

With these and other objects in view, the 30 invention consists in the novel construction, arrangement and formation of parts, as will be hereinafter more fully described, claimed and illustrated in the accompanying drawings, forming a part thereof, in which:

Figure 1 is a perspective view of the improved grave vault.

Fig. 2 is a transverse section taken on the line 2—2 of Fig. 1.

Fig. 3 is a detail horizontal section taken 40 on the line 3—3 of Fig. 1.

Fig. 4 is a plan view of the bottom wall section.

Fig. 5 is a detail perspective view of one 45 of the side walls.

Fig. 6 is a perspective view of one of the end walls.

Fig. 7 is a detail section on the plane of 50 line 7—7 of Fig. 3.

Referring to the drawings in detail, 55 wherein similar reference characters designate corresponding parts throughout the several views, the numeral 1 generally indicates the improved grave vault which includes the side walls 2, the end walls 3, the lower wall 4, and the top wall 5.

The lower wall 4 is of substantially rectangular formation and includes the longitudinally extending grooves 6 positioned adjacent the longitudinal edges of the walls 60 and the transverse grooves 7 arranged adjacent the side edges of the walls. The grooves are formed in the top surface of the bottom wall and form means for receiving the tongues formed on the side and end walls, 65 as will be hereinafter more fully described.

Each of the side walls 2 includes a substantially rectangular flat body having a downwardly extending tongue or rib 8 formed on its lower face which is adapted to 70 fit into the longitudinally extending grooves 6 formed in the lower wall. The rib or tongue 8 extends flush with the inner surface of the side wall. The side walls are each provided with vertical grooves positioned 75 adjacent to the side edges thereof and are formed in the inner face of the side walls and extend from the top edges to the lower edges thereof.

The end walls 3 are each provided with 80 the depending lower rib or tongue 10 which is adapted to fit in the transverse grooves 7 formed in the lower wall and these tongues or ribs are formed on the lower wall of the end walls adjacent to the inner surface 85 thereof. The side walls are also provided with the outwardly extending vertical ribs 11 formed on their side edges and these ribs or tongues extend flush with the inner edge of the end walls and are adapted to fit in the 90 grooves 9 formed in the side walls 2.

The top wall 5 includes a rectangular body having the inwardly extending enlargement 5', which is adapted to fit in the vault and engage the side and end walls thereof. The 95 enlargement defines outwardly extending flanges 13 the lower surfaces of which are adapted to rest upon the upper surface of the side and end walls.

As clearly shown in Figs. 2 and 3 of the 100 drawings, the walls are reinforced by wire netting 15 so as to provide a strong and durable construction. The body of the wall is formed of cement mixture of cement and sand and the inside of the same is lined with 105 Keene cement.

In assembling the sections, the side walls 3 are first placed in position with the tongues or ribs 8 in engagement with the longitudinally extending grooves 6 in the lower 110 wall. The end walls are then placed in position and the tongues 11 are placed in

the grooves 9 formed in the side walls and the end walls 3 are slid downwardly until the lower tongue 12 fits in the transverse grooves 7.

5 During the assembling of the sections, the cement is poured into the grooves so as to form a solid airproof and watertight vault.

10 The meeting surfaces of the sides, end and top walls are serrated, as shown in the drawings and cement is poured into these serrated portions, which effectively seals the lid in position.

15 From the foregoing description, it can be seen that an improved concrete vault is provided, which is formed of sections, that is exceedingly simple and durable in use.

20 In practice, I have found that the form of my invention illustrated in the accompanying drawings and referred to in the above description, as the preferred embodiment, is the most efficient and practical; yet realizing the conditions concurrent with the adoption of my device will necessarily vary, I desire to emphasize that various minor 25 changes in details of construction, proportion and arrangement of parts may be resorted to, when required without sacrificing any of the advantages of my invention as set forth.

What I claim as new is:

A concrete grave vault comprising a bottom section having longitudinal grooves in its upper face and opening upon the ends thereof and transverse grooves in its upper face connecting with said longitudinal grooves 35 adjacent the corners of the bottom section, side sections having reduced lower edges for engagement in the longitudinal grooves in the bottom section and provided in their inner faces with vertical grooves adjacent 40 the ends thereof, end sections having reduced lower edges for engagement in the transverse grooves of the bottom section and reduced vertical edges for engagement in the vertical grooves of the side sections, 45 and a cover section having its main portion depending for engagement between the side sections and the end sections, the lower face of the cover section around the depending portion thereof and the upper faces of said 50 sides and ends having interfitting serrated edges.

In testimony whereof I affix my signature in presence of two witnesses.

JOHN E. MITCHELL.

Witnesses:

F. W. MORTON,
R. L. LINDSAY.
